GEORGE WASHINGTON MEREDITH, OF WICHITA, KANSAS, ASSIGNOR TO
MILO R. MEREDITH, OF WABASH, INDIANA.

CIGAR-VENDING MACHINE.

No. 823,955.

Specification of Letters Patent.

Patented June 19, 1906.

Application filed December 7, 1905. Serial No. 290,728.

To all whom it may concern:

Be it known that I, GEORGE WASHINGTON MEREDITH, a citizen of the United States, and a resident of Wichita, in the county of Sedgwick and State of Kansas, have invented certain new and useful Improvements in Cigar-Vending Machines, of which the following is a specification.

My invention relates to vending-machines in which articles of merchandise are discharged from a stock held for sale by working and manipulating an operating-handle.

Although applicable in most of its features to the sale of any kind of merchandise which is done up in packages of approximately uniform size, it is especially intended for the sale of cigars.

Devices for selling cigars in this way have heretofore been employed; but they lacked a range of sale to cover the various grades and prices of cigars in a simple and practical way. My machine provides for an extension of the function of the machine to the sale of one cigar for five cents, two for five cents, three for five cents, one for ten cents, three for ten cents, one for a quarter, three for a quarter, six for a quarter, or any other number of cigars for a single coin value up to one dollar.

Figure 1 is a vertical longitudinal section of the vending-machine. Fig. 2 is a detail view showing a modification of the delivery-gears. Fig. 3 is a plan view of the vending-machine and the superposed box of cigars. Fig. 4 is a vertical transverse section on line 4-4 of Fig. 1, and Figs. 5 and 6 are details showing modifications of the delivery-gears.

Referring to the drawings, a rectangular metallic framework D', Figs. 1, 3, and 4, carries near its upper surface two horizontal shafts 1 and 2, arranged in bearings, one at the front and the other at the back end of the frame. To the back shaft 1, Fig. 4, are rigidly attached two sprocket-wheels 3 3, and to the front shaft 2 are rigidly attached two sprocket-wheels 4. Around each pair of sprocket-wheels 3 4 there extends an endless chain belt 5, and these chain belts are connected by cell-belts, each composed of a flat base part 6, lying parallel to the chain and the bent wing portion 7 standing at right angles to the part 6 and terminating at its free edge in a round rib 8, or a crimp or turned-over edge. This round free edge forms a stiffening-rib

which prevents the edges of the wings from being bent and also prevents them from scratching or skinning the cigars, as herein-after described. The part 6, with its wing 7, coöperating with the wing 7 next in front of it, forms a cell, as in Fig. 1, to receive the cigar, and the ends of each cell are closed by end flanges 9, Figs. 1 and 4, which prevent the endwise displacement of the cigars.

The front shaft 2 of the cell-belt is provided at one end with a rigidly-attached gear-wheel 10, Fig. 1, which receives motion from a subjacent gear-wheel 11 on a transverse shaft 2^a, journaled in the framework. The gear-wheel 11 has rigidly attached to its side a disk 12, with two diametrically arranged ratchet-teeth 13 13, which are preferably located on its periphery. This shaft and gear 11 are rotated by a gear-wheel 14, which is the last gear of the train of wheels actuated by a clock-spring motor 15, whose main shaft bears a bevel-gear 16, meshing with another bevel-gear 17 on a shaft 18, whose squared end receives a key by which the spring-motor is wound up. This spring-motor, through gears 10 and 11, serves to drive the endless cell-belt, which carries and delivers the cigars. When the machine is at rest, these gears are locked by a detent 19, Fig. 1, pivoted at its rear end to the framework and having a tooth 20, adapted to strike against one of the ratchet-teeth 13 of the disk below. This detent is pressed down by a coil-wire spring 21, and may be elevated by the operator through any suitable lever, push-button, or handle of any kind, or by a coin-controlled mechanism, which forms no necessary part of this invention. When the end 22 of the detent is elevated and its tooth 20, Fig. 1, is withdrawn from the tooth 13 of the ratchet-disk, the motor mechanism is unlocked, and it then turns the gears 10 and 11, and with them the cell-belt, until the detent takes up against the other ratchet-tooth 13. To hold the cell-belt up to its proper advance, as against back movement, a drag-pawl 32, Fig. 3, is hinged to the framework and drags upon the periphery of the toothed gear-wheel 10.

The arrangement of the gears 10 and 11 and the two ratchet-teeth 13 13 of the device just described is such as to cause every lifting movement of the detent 19 to discharge one cigar only and such as would be required

to discharge one cigar for five cents, one for ten cents, or one for a quarter. This is accomplished, as seen in Fig. 1, by making the gear 10 with three times as many teeth as 5 the gear 11, using two diametrically opposite ratchet-teeth 13 13 and so constructing the sprocket-wheel of the cell-belt that a complete revolution of the sprocket-wheel moves the cell-belt a distance of six cells.

- 10 Then one complete revolution of gear 11 (one-third of gear 10) will move the cell-belt two cells. As there are two ratchet-teeth 13 13 to the wheel 11, it is stopped at every half-revolution, which gives the necessary 15 movement of one cell to discharge one cigar each time the key, push-button, or other operating-handle is manipulated.

I will now proceed to describe the relation of the cigar-discharging mechanism, the 20 cigar-box, and the intermediate parts, reference being had to Figs. 1 and 4. This is an important and distinctive part of my invention and one upon which I desire to lay especial emphasis, since endless carrier-belts 25 have heretofore been used with vending-machines, but operating upon an entirely different principle from mine.

In presenting in a general way the distinguishing characteristics I would say that 30 when the box of cigars is to be placed in the machine the bottom of the box is first removed and the box is placed upon one of the vending-machines and the cigars placed back in the box as it rests above the vending-machine. The box is clamped and held stationary and the cigars are then fed out to the subjacent cell-belt or carrier by a process which resolves them into a series of vertical tiers, and my system feeds the cigars always 35 from the remote or inner end of the box, carrying them along under the superposed cigars of the tier in front of them as the cell-belt moves to the front. This process avoids feeding the cigar-box along, and thus renders 40 the apparatus very much more compact, as a plurality of vending-machines with their superposed cigar-boxes may be placed side by side and close to each other in the same case, thus permitting the employment of 45 many such machines in a relatively small case.

For quickly adjusting and firmly holding the cigar-boxes above each machine there is arranged upon one side of the upper edge of 55 the framework a standing flange 34, Fig. 4, against which the lower outside edge of the side of the box is made to abut. Another standing flange 35, Fig. 1, is arranged on the end of the framework at its upper side and 60 projects inside the box and lies immediately against the end wall of the box. On the top of the framework on the opposite side from the standing flange 34 are pivoted (see Fig. 3) two sharp-pointed spring-dogs 36 36.

65 These converge toward the box, and their

pointed ends are made to penetrate the soft wood of the box to hold it firmly in place in connection with the standing flanges 34 35, so that the box cannot shift its position. The spring-dogs 36 lie in a horizontal 70 plane and are in the nature of thin blades of an elastic character, and when they are to be entered into the wood of the box they are first sprung up some distance, as in Fig. 4, so that they tend when seated in the box to hold 75 the box down upon the table-surface with a spring action, as well as to prevent its displacement in a horizontal plane.

Extending crosswise the frame at its upper surface and close down to the rib edges of the 80 cell-wings on the belt are secured a series of fixed horizontal rods 37, Fig. 3. These are arranged parallel to each other at a distance a little greater than the width of a cigar and extend over the whole of the upper surface 85 of the framework. To each one of these stationary rods 37 there is rigidly attached a thin vertical partition-blade 38, and also a hinged and swinging leaf 39. The blades 38 project up above the table-surface of the 90 framework and through the cigars in the box, as seen in Figs. 1 and 4, and separate them into a series of vertical tiers. The lower cigar of each vertical tier rests in a cell of the carrier-belt with the hinged leaf 39 lying 95 upon and lapping across it. The other cigars of each tier rest upon the leaves 39, which latter form a sort of false bottom for said upper cigars.

As the cell-belt moves forward in the direction of the arrow all of the cigars in the cells of the belt are carried forward under the superposed cigars, which are not disturbed. Abrasion of the cigars is prevented by the smooth leaves 39 and also by the round ribs 100 8 of the cell-belt. Now when the box of cigars has had its bottom removed and has been placed upon the framework and the cigars filled in between the stationary partition-blades 38 the cell-belt in moving forward under the action of the motor mechanism carries forward the lower row of cigars as formed of the bottom cigar of each vertical tier, the upper ones not being disturbed until an empty cell comes beneath the rear vertical tier of cigars. When this takes place, the hinged leaf 39 of that tier falls and the cigars above it drop down into the cells as they pass under. It will be seen therefore that the cigars in the front tier are the last ones to be 110 fed down, the cigars feeding downward into the cells of the belt from the rear vertical tier first, and when they are all received into the belt the next tier in front is fed down by the falling of the hinged leaf. In this connection it will be seen that the hinged leaves riding on the subjacent cigars in the cell-belt act as false bottoms to hold up the superposed cigars and form a smooth surface between the lower row of cigars and those 115 120 125 130

above it, which prevents abrasion and skinning of the wrappers. The main object of the leaves 39 is to accomplish the continuous delivery of cigars from the box, as the cigars will not only be skinned, but will without the leaves 39 invariably get caught and be ground up and eventually stop the machine, the cigars getting caught between the wings 7 and the preceding cross-bar. The leaf 39 holds the cigars up, this leaf in turn being held up by the moving wing 7 until such time that when the leaf drops from the moving wing 7 (either back to the succeeding wing, as in the rear tier, or the succeeding cigar, as in all other tiers) the wing 7 will be a little in advance of the superposed cigars, so that said superposed cigar falls back instead of in front of the moving wing 7. Thus these leaves are absolutely necessary for continuous delivery, whether from one tier or a series of tiers.

By the above-described mode of feeding the cigars from the back end of the box and carrying them in a forwardly-moving row under the cigars in front the cigar-box and partition-blades 38 are maintained stationary, and this avoids the necessity of having to feed the entire box of cigars along guide-ways, which would require the vending-machines to be spaced twice the distance apart if arranged side by side and would require an inclosing case twice as large.

In order to hold the cells of the carrier-belt in horizontal alinement, the base-plates 6 of the cells are extended at the ends (see Fig. 4) and are received in the flanged or grooved guide-strips 40, of which there is one on each side.

I have already described in connection with Fig. 1 how a single cigar is discharged for a single coin of five, ten, or twenty-five cents. I will now describe how one, two, three, or six cigars may be discharged for a single coin. For this purpose the vending-machines are made exactly like the one already described, with the exception of the driving-gears.

For machines which discharge two cigars for five cents or two for twenty-five cents the gears are as shown in Fig. 2. The cells 10 and 11 bear the same ratio of teeth (three to one) as in Fig. 1; but the disk 12^a has only one ratchet-tooth 13^a. Now as a complete revolution of sprocket-wheel 4 moves the cell-belt six spaces one complete revolution of the disk 12^a turns the gear 10 a third of a revolution, and one-third of six is two, which discharges the contents of two cells each time the operating-handle is worked.

For the machines which discharge three cigars for a coin value of five, ten, or twenty-five cents the gears are arranged as in Fig. 5, in which the wheels 10^b and 11^b are equal in size and of the same number of teeth, so that

65 a complete revolution of either gear moves

the belt six spaces and a half-revolution three spaces, the half-revolution being secured by simply using two diametrical ratchet-teeth-13^b 13^b.

To discharge six cigars for twenty-five cents or six for ten cents or six for five cents, the same gears are used as in Fig. 5, but only one ratchet-tooth 13^c is used, as shown in Fig. 6. This will give a complete revolution of the sprocket-wheels and moves the cell-belt six spaces for each movement of the operating-handle.

In carrying out my invention I would have it understood that I do not confine myself to the exact construction and arrangement of the machine as herein shown, as various changes in construction and arrangement may be made without departing from my invention as set forth in the claims.

Having thus described my invention, what I claim as new, and desire to secure by Letters Patent, is—

1. A vending-machine, comprising a framework, an endless belt carrying cells, actuating devices for the cell-belt, a series of stationary partition-blades arranged parallel to each other above the cell-belt transversely thereto and fixed at their lower edges rigidly to the framework, means for holding the articles between the partition-blades in vertical tiers, and means for feeding the rearmost tier beneath the superposed tiers in front of it.

2. A vending-machine, comprising a framework, an endless belt carrying cells, actuating devices for the cell-belt, a series of stationary partition-blades arranged parallel to each other above the cell-belt transversely thereto and fixed at their lower ends rigidly to the framework, leaves hinged at the lower edges of the partition-blades and arranged to hold the superposed articles and allow them to drop successively, as described.

3. A vending-machine, comprising a framework, an endless belt carrying cells, actuating devices for the cell-belt, a series of parallel horizontal rods extending across and attached at their ends to the frame above the cell-belt, a series of upwardly-projecting and parallel partition-blades attached at their lower edges to the horizontal rods, and a series of pivoted leaves hinged to said rods and arranged to form automatically-dropping false bottoms, as described.

4. A vending-machine, comprising a framework, an endless belt carrying cells, said cells being formed of flat plates having right-angular wings with rounded and stiffened outer edges, stationary upwardly-projecting partition-blades fixed to the framework, and means for moving the cell-belt under the partition-blades.

5. A vending-machine, comprising a framework, an endless belt carrying cells, said cells having end extensions, parallel horizontal guides arranged in the framework to receive

- the cell extensions, a series of parallel upwardly-projecting partition-blades fixed in stationary position above the cell-belt and extending down close to the edges of the cells, 5 as held up to true alinement by the guides.
6. A vending-machine, comprising a framework, an endless cell-belt, stationary partition-blades arranged above the cell-belt and projecting upwardly from the framework and 10 adapted to enter the articles held for sale in their original packing-box, and means for actuating the belt.
7. A vending-machine, comprising a framework, an endless cell-belt, stationary partition-blades arranged above the cell-belt and projecting upwardly from the framework and 15 adapted to enter the articles held for sale in the original packing-box, means for locking said box against displacement, and means 20 for actuating the belt.
8. A vending-machine, comprising a framework, an endless cell-belt, stationary partition-blades arranged above the cell-belt and projecting upwardly from the framework and 25 adapted to enter the articles held for sale in the original packing-box, means for locking said box both against horizontal and vertical displacement, and means for actuating the belt.
30. 9. A vending-machine, comprising a framework, an endless cell-belt, actuating devices for the same, stationary partition-blades projecting upwardly from the framework and adapted to enter the articles held for sale in 35 the original packing-box, stationary vertical abutment-flanges arranged on top of the framework for the packing-box to abut against, and pivoted dogs having sharpened
- teeth adapted to enter the material of the box and hold it against the abutment-flanges. 40
10. A vending-machine, comprising a framework, an endless cell-belt, actuating devices for the same, stationary abutments projecting upwardly from the framework, and toothed dogs pivoted to the framework 45 to swing horizontally and constructed as elastic bars to be sprung up and be put under downward stress to hold the box down on the framework.
11. A vending-machine, comprising an endless belt having cells forming carriers, a driving-axle with sprocket-wheels distending the belt, a gear-wheel fixed rigidly on the sprocket-axle, a second gear-wheel meshing with the first-named gear-wheel, the two 50 gears being arranged with a multiple ratio of teeth to advance the belt a predetermined but variable number of cells and a motor with starting and stopping mechanism.
12. A vending-machine, comprising an endless belt having cells forming carriers, a driving-axle with sprocket-wheels distending the belt, a gear-wheel fixed rigidly on the sprocket-axle, a second gear-wheel meshing with the first-named gear-wheel and having 55 teeth whose number is a multiple of the number in the first-named gear, a disk with stop-teeth correlated in number to the gear-wheels and cells of the belt, a detent for the toothed disk and a motor mechanism substantially as 60 described.
